No. 768,772.

PATENTED AUG. 30, 1904.

W. VON ROUGEMONT.

AUTOMATIC REFRIGERATING APPARATUS FOR USE IN CONNECTION WITH
FERMENTING OPERATIONS.

APPLICATION FILED MAY 29, 1903.

NO MODEL.

UNITED STATES PATENT OFFICE.

WALTER VON ROUGEMONT, OF RITTERGUT HOHBURG, GERMANY.

AUTOMATIC REFRIGERATING APPARATUS FOR USE IN CONNECTION WITH FERMENTING OPERATIONS.

SPECIFICATION forming part of Letters Patent No. 768,772, dated August 30, 1904.

Application filed May 29, 1903. Serial No. 159,387. (No model.)

To all whom it may concern:

Be it known that I, WALTER VON ROUGEMONT, a subject of the German Emperor, residing at Rittergut Hohburg, near Wurzen, Saxony, Germany, have invented certain new and useful Improvements in Automatic Refrigerating Apparatus for Use in Connection with Fermenting Operations; and I do hereby declare the following to be a full, clear, and exact 10 description of the invention, such as will enable others skilled in the art to which it appertains to make and use the same.

My invention relates to improvements in apparatus for automatically controlling the supply of water to a pipe used for maintaining the required temperature in a fermenting-vat such as is used in distilleries; and it consists in the construction, combination, and arrangement of devices hereinafter described and 20 claimed.

In the accompanying drawings, Figure 1 is an elevation, partly in section, of a refrigerating or attemperating apparatus embodying my invention; and Fig. 2 is a detail sectional view showing the water-supply-controlling valve and its connections.

The water-supply valve *n* of the refrigerating or attemperating pipe *r*, having the coil *q* in the vat *a*, is connected with a contact-thermometer *b*, arranged in the fermenting-vat *a*, by means of suitable actuating parts as well as by an electric circuit *d d'*, so that upon any undue increase of temperature in the fermenting-vat the circuit *d d'* is closed by the column of mercury, and thereby the valve *n* is opened, the pipe *r* being thus put in action owing to the passage of water therethrough from the cistern *p*. If in connection therewith the temperature in the fermenting-vat decreases again to such an 30 extent that the circuit *d d'* is interrupted by the falling of the column of mercury, the valve *n* closes, thereby putting the attemperating-pipe out of action. If very considerable cooling is to be effected, it is advisable 40 so to connect the pipe *r* with the water-supply that the water shall flow through said pipe at the pressure prevailing in the water-supply, as indicated in Fig. 1.

The valve is so constructed that it can be 50 connected with a supply of water under pressure without its being necessary to employ a powerful electric current for opening the

valve, but so that the valve can be operated by a feeble electric current.

The valve *n* is supported by a rod *v*, (see 55 Fig. 2,) the upper end of which is so connected with the armature *h* of the electromagnet *g* that when the magnet is excited and the armature *h* is attracted thereby the valve is raised from its seat by the armature, thereby 60 opening the passage for the water.

In order that the feeble current may suffice for raising the valve *n*, which is under pressure, from its seat, the rod *v* is loosely guided in the valve-cover *w*, so as to avoid friction. 65 To effect a tight packing between the cover *w* and the rod *v*, a flexible casing *x* is fixed to the central portion of the cover, its lower end being connected with the rod *v* and the casing *x* being put under tension by means 70 of a spring *f*, arranged in the interior thereof. The movable parts are balanced by the balance-lever *h'*, the pivot of which is indicated at *i*.

By this construction, combination, and arrangement of devices the valve-body, with the actuating parts belonging thereto, can be so easily moved that the weak electric current is at all times sufficient for opening the passage for the flow of water through the pipe *r* 80 and the coil *q* in the fermenting-vat.

What I claim, and desire to secure by Letters Patent, is—

In apparatus of the class described, the combination of a cooling-vat, a water-coil therein, 85 a water-supply element connected to the said coil and including a closed valve-box, a valve therein to control the supply of water to the coil, a rod attached to said valve and operating in an opening in the valve-box, a flexible 90 casing in the latter, around said opening and rod, and having one end attached to and movable with the rod, a balance-lever attached to said rod, an armature attached to said balance-lever, an electromagnet, and a circuit-closing 95 thermometer in the vat, and in electrical connection with the windings of the electromagnet, substantially as described.

In testimony whereof I have affixed my signature in presence of two witnesses.

WALTER VON ROUGEMONT.
